Primary Examiner — Kimberly Barnes*Assistant Examiner* — Sarah A Nguyen(57) **CLAIM**

The ornamental design for a mop head base, as shown and described.

DESCRIPTION

FIG. 1 is a front, top and right-side perspective view of a mop head base showing my new design;

FIG. 2 is a rear, bottom and right-side perspective view thereof.

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view, of circled portion 9, of FIG.2, thereof; and,

FIG. 10 is another front, top and right-side perspective view shown in an alternate position thereof.

The broken lines throughout the drawing figures depict portions of the mop head base that form no part of the claimed design.

The dot-dash broken lines depict the boundaries of the FIG. 9 enlargement that forms no part of the claimed design.

1 Claim, 10 Drawing Sheets(56)
